SHOE STRETCHING DEVICE

Andrew Kanell, Chicago, Ill.

Application February 4, 1935, Serial No. 4,824

12 Claims. (Cl. 12—128.6)

My invention relates to shoe stretching devices and it has to do more particularly with a device of this character adapted to stretch the entire shoe lengthwise and the toe portion thereof sideways.

One of the objects of my invention is to provide an improved shoe stretching device of the foregoing character which is of simple construction, which may be cheaply manufactured, and which may be operated easily and quickly to stretch shoes to the desired extent.

Another object is to provide a device of the foregoing character having improved flexibility in adjustment and in which stretching adjustments may be carried out by the manipulation of but few parts.

A further object is to provide an arrangement whereby stretching of the shoe lengthwise and of the toe portion thereof sideways may be carried out by a single means adapted to apply great stretching pressure in the directions stated.

Additional objects are to provide a device of the foregoing character wherein the toe and heel units are adjustably connected by means including resilient members that constantly tend to return and yieldably hold such units in their normal non-expanded condition; and to provide a shoe stretching device that is exceptionally strong and durable, and which is capable of being readily built up to desired shape and size suitable for stretching different shoes.

Other objects and advantages will become apparent as this description progresses and by reference to the drawing, in which,—

Fig. 1 is a top plan view, partially in section, of one form of shoe stretching device embodying my invention;

Fig. 2 is a longitudinal section through the structure shown in Fig. 1;

Fig. 3 is a section taken substantially on the line 3—3 of Fig. 2; and

Fig. 4 is a detached fragmentary view of latch means employed in retaining the stretcher sections in longitudinally-adjusted positions.

The structure shown in the drawing includes a relatively adjustable toe unit T and heel unit H. Both of these units are, preferably, made of some suitable metal, for example, an aluminum alloy, which provides durability and lightness in weight. However, it will be readily appreciated that any other suitable material may be employed without departing from my invention.

The toe unit comprises a pair of similar sections 10 of such shape that, when they are assembled together, they have the general outline

shape of the toe of a shoe. The sections 10 are preferably shaped and sized for a comparatively small shoe, and they may be readily adapted for larger size and different-shaped shoes by the use of adapter sections such, for example, as the section 11 shown in Figs. 1 and 2. The adapter sections 11 are supported upon the toe sections 10 by pins 12 engaging suitably provided openings 13 in the latter. The adapter sections 11 may take various shapes and sizes, so that substantially the entire size range of shoes may be readily stretched with the structure shown.

The toe sections 10 are supported in connected relation by a T-shaped member 14 having at its front end oppositely directed and substantially flat arms 15 with elongated slots 16 therein. The toe sections 10, adjacent their forward ends, are provided with recesses 17 that receive the arms 15. Pins 18 carried by the toe sections pass through the arm slots 16 and thereby loosely connect the toe sections 10 to the member 14 in such a way that the toe sections may be extended laterally of the member 14 and/or be hinged angularly with respect thereto.

Each toe section 10 is provided, in its rear half portion, with a recess 19 of triangular-like shape in longitudinal direction and, when the toe sections are assembled, these recesses 19 provide a wedge-cavity 20, the side walls of which converge laterally inward from the rear end of the toe unit. This cavity 20 is adapted to receive a wedge-spreading member 21 for extending the toe sections 10, as will be described more fully herein-after. The rear ends of the toe sections 10, directly above the wedge-cavity 20, are shaped to provide a ledge-and-abutment 22 adapted to be engaged by the T-head portion of the member 14 (Figs. 1 and 2) for simultaneously moving both of the toe sections in a longitudinal direction, and to like extent, when the member 14 is moved in that direction. The movement of the toe sections 10 may be further facilitated, if desired, by providing upon the rear of one of the sections a cross-member 23 that engages behind the other section so that when the former section is moved the latter will also be similarly moved; however, this construction may be readily omitted and the T-head 22 depended upon, solely, to effect the movement in question. The cross-part 23 has utility in partially maintaining the proper assembly of the toe unit parts during adjustment movements, but it is not entirely necessary for that purpose.

The heel unit includes a pair of similar sections 24 that are fixedly secured together in any

desired manner. The inner, adjacent faces of the heel sections 24 are shaped to provide, in the assembled condition of such sections, a bore 25 for slide-reception of a rack bar 26; recesses 27 5 and 28 in which the ends of a shaft 29 carrying a pinion 30 are journaled; recesses 31 in which the ends of a shaft 32 carrying a nut 33 are journaled; and an enlarged recess 34 accommodating springs 35, the purpose of which will be 10 made clear hereinafter.

The rack bar 26 is fixedly secured to, and forms an extension of, the member 14; and it is provided with teeth 36 that engage the pinion 30. One end of the shaft 29 supporting this pinion 15 is extended through the wall of the supporting heel section where it receives a handle member 37. By rotating the handle 37 the rack bar 26 and member 14 are adjusted longitudinally. The rack bar 26 is also provided with a handle 45 and 20 longitudinal adjustment movement thereof may be effected by pressing forwardly on this handle. The foregoing parts are held in their longitudinally-adjusted position by a latch member 38 normally supported in engagement with the teeth of 25 the pinion 30 by an arm 39 pivotally supported at 40 and constantly actuated by spring 41 to urge the latch 38 into engagement with the pinion. It will be noted that the latch nose 38a is so shaped that, upon rotation of the pinion 30 in a 30 counterclockwise direction (Fig. 2), the latch will be cammed out of stop-engagement with the pinion; but, when the pinion tends to rotate in the opposite direction (as by movement of the rack bar 26 in that direction), the latch serves 35 as a positive stop against such movement. In that case, the latch 38 may be released by depressing the free end of the arm 39 for return movement of the rack bar 26 and the member 14. Adjustments of the foregoing character may be 40 employed in initially setting up the stretcher in the shoe. Actual longitudinal stretching operation is, preferably, carried out by adjusting mechanism that will now be described.

The adjusting wedge or wedge-spreading member 21 has the general outline wedge-shape of the wedge cavity 20. The top part of the forward end portion of the wedge 21 is cut away, as shown in Fig. 3, to provide a shallow front portion, at the rear of which is a vertical shoulder 46. This 45 shoulder is adapted to engage both of the toe sections at the rear thereof immediately above the wedge cavity 20, so that, upon propelling such wedge member longitudinally, the toe sections will be moved in that direction to like extent. The wedge member 21 is rockably supported for 50 reciprocation so that it may be moved to engage either its shoulder 46 with the rear of the toe sections or to enter the wedge cavity 20, in which latter case, longitudinal movement thereof expands the toe sections.

The wedge member 21 is supported for the foregoing adjustment movements as follows: It is secured, as by pin 47, to the forward end of a 55 screw shaft 48 that is threadedly engaged with the nut 33. The screw rod 48 passes rearwardly through an enlarged opening 49 at the back of the heel unit and it is of sufficient length to extend beyond the rock bar handle 45 where it receives a handle 50. The nut carrying shaft 32 and its nut 33 are adapted to rock so that the screw bar 48 may be rocked vertically (about the horizontal axis of the shaft 32) to an extent permitted by the opening 49. The wedge member 21 60 may, in this manner, be rocked to engage behind

the two sections 10 or to enter the wedge cavity 20, as above described.

The toe and heel units are further connected together by the pair of springs 35. As will be seen from Fig. 2, extensible coil springs are employed for this purpose, there being one spring 55 for each toe unit. The forward end of each spring 35 is connected to its respective toe unit by a slot-and-pin means 51 (only one shown), and the rear end of each spring is connected to 10 the heel unit by a pin 52 (only one shown). The springs 35 (Fig. 2) pass through longitudinally slotted portions 53 (only one shown) in the forward part of the heel unit in such a way that expansion and contraction thereof may readily 15 take place during the adjustments of the heel and toe sections. These springs, as will be observed from Fig. 2, oppose adjustment of the toe unit away from the heel unit and also yieldably oppose spreading or lateral expansion movement of the 20 toe sections. Since the springs are placed under tension, under these adjustment conditions, it will be seen that the springs 35 will automatically return the toe section and the toe unit as a 25 whole to, and hold them in, the normal positions of Figs. 1 and 2. The springs 35 further tend to cushion the adjusting movements of the parts and tend to maintain such parts in proper position when the device is not in use.

It is believed that operation of my invention 30 will be readily understood from the foregoing. Briefly, when it is desired to stretch a shoe, the device is inserted in the shoe and initially adjusted to the length thereof by actuating the 35 rack bar 26 to extend the toe unit as already described. The wedge member 21 is then advanced and the handle 50 rocked downwardly to the full-line position of Fig. 2 to engage the wedge member 21 behind the toe sections and extend the toe 40 unit with sufficient pressure to stretch the shoe 45 lengthwise. When this has been accomplished, the latch 38 serves to hold the toe unit in its longitudinally adjusted position. This permits the handle 50 to be rocked upwardly to the dotted 50 line position of Fig. 2 wherein the wedge member 21 is caused to enter the wedge cavity 20 and expand the toe sections laterally as the handle 55 and screw rod 48 are actuated in the manner above described. This causes the toe of the shoe to be stretched laterally. After the stretching operation has been completed, the wedge member 55 55 21 may be retracted so that, when the latch 38 is released, the springs 35 will return the toe unit and the sections thereof to their normal positions wherein the device may be removed from the shoe.

Although I have shown only one form of device embodying my invention, it will be understood that various changes in details and arrangements of parts may be made without departing from the spirit and scope of my invention as defined by the claims that follow.

I claim:

1. In a shoe stretching device, a toe unit having laterally expandable toe sections, a heel unit, means connecting said units for longitudinal adjustment of said toe unit relative to said heel unit, means carried by said heel unit and adjustable to one position to engage said toe unit and adjust the same longitudinally to stretch the shoe lengthwise, said second-mentioned means being adjustable to another position to engage said toe sections and expand the same laterally, and means for holding said toe unit in any longitudinally adjusted position independently 65 70 75 75

of said first means whereby said first means may be adjusted to its toe section expanding position in any longitudinally expanded position of said toe unit.

5. 2. In a shoe stretching device, a toe unit comprising a pair of laterally expansible sections shaped to fit the toe portion of a shoe, a heel unit shaped to fit the heel portion of a shoe, means connecting and supporting said toe and heel units for relative longitudinal adjustment and for lateral expansion adjustment of said toe sections, a member carried by said heel unit and engageable with said toe unit to adjust the latter longitudinally, and also engageable with said toe unit 10 in any longitudinally adjusted position thereof to expand said toe sections laterally, and releasable means for holding said toe unit in any longitudinally adjusted position.

3. In a shoe stretching device, a toe unit having a pair of expansible toe sections, each said section having a recess therein of such shape that in the assembled condition of said sections a wedge cavity converging inwardly from the rear of said toe unit is provided, a heel unit, means connecting said toe and heel units for longitudinal adjustment of said toe unit, and means for adjusting said toe unit longitudinally and for also expanding said toe sections which includes, a wedge member adapted to enter said wedge cavity and also provided with an abutment adapted to engage the rear of said toe unit to one side of said wedge cavity, a support for said wedge member carried by said heel unit in such a way that it is adjustable rockably and longitudinally, and means for adjusting said support longitudinally and for rocking it in one direction to engage said wedge member abutment with said toe unit to adjust the latter longitudinally and for rocking it in the opposite direction to engage 30 said wedge member in said wedge cavity so that upon continued longitudinal adjustment of said support said toe sections are expanded laterally.

4. In a shoe stretching device, a toe unit including a pair of similar sections, a heel unit, a support member carried by and adjustable longitudinally of said heel unit, pivot means connecting the forward end of said support member to the forward ends of said toe unit sections whereby said toe unit sections may swing laterally with their rear ends free, longitudinally adjustable means carried by said heel unit and adjustable laterally to one position for positively engaging the rear of said toe unit for moving the latter away from the heel unit and also adjustable to another position for spread-engaging said toe sections to expand the latter, and means for adjusting said adjustable means both longitudinally and laterally.

5. In a shoe stretching device, a toe unit including a pair of similar sections, a heel unit, a support member carried by and adjustable longitudinally of said heel unit, pivot means connecting the forward end of said support member to the forward ends of said toe unit sections whereby said toe unit sections may swing laterally about said pivot means, longitudinally adjustable means carried by said heel unit and adjustable laterally to one position for positively engaging the rear of said toe unit for moving the latter away from the heel unit and also adjustable to another position for spread-engaging said toe sections to expand the latter, means for adjusting said adjustable means both longitudinally and laterally, and spring means between said heel unit and said toe sections yieldably opposing

both longitudinal and lateral expanding movements of said toe unit.

6. In a shoe stretching device, a toe unit including a pair of similar sections, a heel unit, a support member carried by and adjustable longitudinally of said heel unit, pivot means connecting the forward end of said support member to the forward ends of said toe unit sections whereby said toe unit sections may swing laterally, longitudinally adjustable means carried by said heel unit and adjustable laterally to one position for positively engaging the rear of said toe unit for moving the latter away from the heel unit and to another position for spread-engaging said toe sections to expand the latter, means for adjusting said adjustable means both longitudinally and laterally, latch means carried by said heel unit and releasably engageable with said support member for automatically holding said toe unit in any longitudinal position independently of the 20 position of said adjustable means.

7. In a shoe stretching device, a toe unit including a pair of similar sections, a heel unit, a support member carried by and adjustable longitudinally of said heel unit, pivot means connecting the forward end of said support member to the forward ends of said toe unit sections whereby said toe unit sections may swing laterally, longitudinally adjustable means carried by said heel unit and adjustable laterally to one position for positively engaging the rear of said toe unit for moving the latter away from the heel unit and to another position for spread-engaging said toe sections to expand the latter, means for adjusting said adjustable means both longitudinally and laterally, latch means adapted to engage said support member and hold said units in any longitudinally adjusted position independently of said adjustable means, and spring means connected to said heel unit and said toe sections yieldably opposing both longitudinal and lateral expanding movements of said toe unit and tending to return said toe unit to a normal non-expanded condition when said latch means is released.

8. In a shoe stretching device, a toe unit having laterally expansible sections, a heel unit, means connecting said units for relative longitudinal adjustments, and a single longitudinally adjustable member carried by said heel unit and also laterally adjustable to one position to engage said toe unit and move the latter in longitudinal expanding direction upon longitudinal adjustment of said member and adjustable laterally to another position wherein it expands said toe unit sections laterally when adjusted longitudinally, and means for adjusting said member both laterally and longitudinally.

9. In a shoe stretching device a toe unit having a pair of sections, a heel unit, longitudinally adjustable means securing said toe sections together but permitting lateral expanding movement of said sections, spring means between said toe sections and heel unit for normally retaining said units together, and tiltable means carried by said heel unit for engaging and either advancing said toe sections longitudinally or spreading the same laterally.

10. In a shoe stretcher device, a toe unit having laterally expansible sections, a separate heel unit, and means positively engageable with said toe unit to adjust the same as a whole longitudinally away from said heel unit, said same means being also adapted to engage said toe unit sections to expand the same laterally in any longitudinally adjusted position of said toe unit.

11. In a shoe stretcher device, a toe unit having a pair of laterally expansible sections, a heel unit, a support adjustably carried by said heel unit, means connecting both said toe unit sections to said support so that they are adapted to hinge and expand laterally of said support, means for adjusting said support to adjust both said toe sections simultaneously away from said heel unit, and means for expanding said toe sections laterally in any adjusted position of said toe unit.
12. In a shoe stretcher device, a toe unit having a pair of laterally expansible sections, a heel unit,

a support adjustably carried by said heel unit, means connecting both said toe unit sections to said support so that they are adapted to hinge and expand laterally of said support, means for adjusting said support to adjust both said toe sections simultaneously away from said heel unit, means for expanding said toe sections laterally in any adjusted position of said toe unit, and spring means connecting said toe sections to said heel unit and yieldably opposing all adjusting movements of said toe unit and the sections thereof. 5 10

ANDREW KANELI,
